Attorney

UNITED STATES PATENT OFFICE.

ALFRED G. F. KUROWSKI, OF BROOKLYN, NEW YORK, ASSIGNOR TO UNDERWOOD TYPE-WRITER COMPANY, OF NEW YORK, N. Y., A CORPORATION OF DELAWARE.

TYPEWRITING MACHINE.

Application filed July 29, 1924. Serial No. 728,833.

This invention relates generally to type-writing machines, and more particularly to registering or counting mechanism attachable to such machines for keeping track of the amount of work.

One feature of the invention is the provision of means for transmitting the motion of the escapement mechanism to a register or counter of the character mentioned, in such manner as to facilitate running a number into the register.

Another feature of the invention embodies the provision of means for mounting the device as a unit upon a machine of the usual standard construction without making any structural changes in the typewriter.

The register may be easily and quickly attached or detached as a unit without interfering with or disturbing any of the other parts of the machine.

A further feature embraces simplified means for properly adjusting the registering mechanism with respect to the escapement mechanism, when in place upon the machine.

The invention involves the use of a comparatively small number of parts, which may be inexpensively manufactured and easily assembled.

Other features and advantages will hereinafter appear.

In the accompanying drawings,

Figure 1 is a rear view of a portion of the frame and escapement mechanism of a type-writing machine with the register in position thereon.

Figure 2 is a view of a conventional escapement-wheel, pinion and rack, such as used in a standard typewriting machine.

Figure 3 is a plan view of the mechanism shown in Figure 1, with parts broken away in section for clearness of illustration.

Figure 4 is a vertical section through the registering mechanism, in the direction of the arrows on line 4-4 of Figure 1.

Reference numeral 10 indicates the frame of a typewriting machine, which includes a transverse portion or base 11 and a vertical standard 12. An escapement-wheel 13 is mounted to revolve with an escapement-shaft 14, which is suitably journaled in a structure 15, supported upon and secured to the base 11 of the frame 10. The usual pinion 16 is fixed to the escapement-shaft

14 and meshes with a rack 17, as shown in Figure 2, the shaft being driven by a suitable motor device (not shown), to impart motion to the rack and cause a carriage (not shown) to move in letter-feeding direction. Escapement-rockers 18 are operated by the usual means, well known in connection with machines of this character, to control the movements of the escapement-wheel and thereby the feeding of the carriage. A lock-nut 19 of the usual rectangular form is received in threaded engagement upon the shaft 14, and it will be noted that the lock-nut is characterized by a pair of long parallel sides 20 and curved narrow sides 21, one of the narrow sides of the nut being cut out at 22, to provide a pair of clamping jaws 23. A countersunk screw 24 serves to draw the jaws 23 together, and, in this manner, the lock-nut may be adjusted and secured upon the shaft 14. The lock-nut 19 due to its peculiar shape provides a camming device and is associated with the registering mechanism, forming the present invention, for the purpose of causing the register to operate. The manner of its functioning with relation to the registering mechanism will appear as the description proceeds.

Thus far, the description has been directed to mechanism commonly used in the Underwood standard typewriting machine and is included herein to show how my improved registering mechanism is applied to a machine for the purpose of keeping track of the amount of work written thereby. The registering mechanism is mounted upon a bracket 25, having a perforation 26 through the upper left portion of the body 25' thereof. A suitable screw 27 threads into the usual screw-threaded hole 28, found upon the left rear standard 12 of a machine of standard construction, the screw projecting slightly beyond the outer face of the standard, so as to be received in the perforation 26 of the bracket 25, and a lock-nut 29 threads onto the projecting end of the screw 27 to secure the bracket firmly to the outer face of the standard. The bracket 25 includes a pair of turned-over ears 30 and 31, which are spaced from and overlie the inner face 12' of the standard 12, the ears being perforated and threaded to receive screws 32 and 33, the ends of which bear against the

face 12' of the standard to hold the bracket in position thereupon. Lock-nuts 34 are provided for the screws 32 and 33. It will be readily apparent that upon properly adjusting the screws 32 and 33, the bracket may be turned angularly about the screw 27 to vary the angle of the bracket 25 with respect to the face 12' of the standard 12. The purpose of this adjustment will appear later in the description. An extension 35 of the body 25' is disposed parallel with the back edge of the base 11 of the machine and is inclined slightly upwardly with respect to said base. The free end 36 of the extension 35 is provided with a boss 37, having a transverse bore 38. A lever 39, having arms 40 and 41, is pivoted for rocking movement upon the extension 35, by means of a stud 42 carried by the lever, which passes through the bore 38, the stud being drilled out and threaded to receive a screw 43, the head of which acts as a stop against the end of the boss 37 to hold the stud in place, sufficient clearance being allowed to permit the stud to turn freely. To limit the upward swing of the arm 41, there is provided upon the extension 35, a stop pin 71, which lies in the path of a notch 72 of said arm. A tension spring 73, having one end fixed to the stop pin 71 and the other end fastened to a stud 74 carried by an ear 75 of the lever 39, yieldingly holds the arm raised and the notch 72 against the stop pin 71. A register or counter 44 is attached to the extension 35, adjacent the body 25' of the bracket 25, by means of screws 45, or in any other suitable manner, and includes the usual shaft 46, which drives indicating dial-wheels within the register 44. Upon the shaft 46 there is mounted a ratchet-wheel 47, having a hub 48, which is reduced at 49 to form a shoulder 50. A lever 51 has an annular perforation of a proper size to be received upon the hub 48 of the ratchet-wheel 47. A collar 52 is received upon the reduced portion 49 of the hub 48 and fits against the shoulder 50. It will be noted, that the diameter of the collar 52 is somewhat greater than the diameter of the hub 48, and thereby provides an annular channel for retaining the lever 51 upon the hub 48, it being understood that sufficient clearness is provided to permit free angular movement of the lever upon the hub. A set-screw 53 passes through a perforation in the collar 52 and then in threaded engagement through the reduced portion 49 of the hub 48 and bears against the shaft 46, thus acting to hold the collar in position upon the hub and at the same time secure the ratchet-wheel 47 to the shaft. The lever 51 has two arms, one of which is designated by the numeral 54 and extends to the point adjacent the free end of the arm 41, which is forked at 55 to receive a pin 56, extending at right angles from the free end of the arm

54. The other arm, which is designated 57, extends in a direction diametrically opposite from the arm 54, the end being turned-down and perforated at 58. A driving pawl 59 is pivoted upon the lever 51, as indicated at 60, and includes a vertically-disposed finger 61, which engages the ratchet-wheel 47 and a depending arm 62, having a perforation 63 in the free end thereof. A tension spring 64, the ends of which are secured within the perforations 58 and 63, causes the finger 61 to be held into yielding engagement with the ratchet wheel 47. A retaining pawl 65 is pivoted at 66 and is urged into engagement with the ratchet-wheel 47 through the medium of a wire spring 67, the object being to prevent the ratchet-wheel from turning about its pivot while the driving pawl is being moved to a position to engage a new tooth. The arm 40 of the lever 39 is offset, as indicated at 68, to extend inwardly of the typewriting machine, and the free end 69 of said arm is disposed directly over the lock-nut 19 of the escapement mechanism and at right angles to the escapement-shaft 14. A roller 70 is mounted upon the free end 69 and is arranged to ride upon the lock-nut 19 to impart motion to the lever 39, when the escapement mechanism is operated as by the striking of the printing keys of the machine.

It will be readily appreciated that when the lock-nut 19 is caused to revolve, the roller 70 will ride up on the inclining face of one of the long parallel sides 20, thence around the curved narrow sides 21 and onto the opposite parallel side 20, thus providing a camming action and causing the lever 39 to partake of a rocking motion against the action of the spring 73 to hold the arm 41 raised. It will also be seen that in rocking the lever 39 about its pivotal point, that is, the stud 42, the forked portion 55 of the arm 41 transmits reciprocating motion to the arm 54 by means of the pin 56, thus causing the lever 51 to rock about its pivot. This action moves the pawl 59 backwardly around the ratchet-wheel 47 to engage a new tooth, and, as the roller 70 rides down on one of the sides 20, the pawl is caused to move upwardly by action of the tension spring 73, to rotate the ratchet-wheel 47, and thereby operate the counter 44.

Vertical adjustment of the extension 35 of the bracket 25, to vary the angle of the extension 35, may be had, as previously described, and such adjustment is provided for the purpose of properly positioning the roller 70 with respect to the lock-nut 19.

It is to be noted that the power required for running a unit into the register is not derived from a single operation of the escapement mechanism, but is contributed fractionally by each of a plurality of operations of the mechanism, thereby so distribut-

ing the required energy as to render practically negligible the effort for driving the register.

Variations may be resorted to within the scope of the invention, and portions of the improvements may be used without others.

Having thus described my invention, I claim:

1. In a typewriting machine, a main frame, escapement mechanism, a camming device actuated upon the operation of said escapement mechanism, a standard at the rear of the main frame, a bracket detachably and adjustably secured to said standard, a register mounted upon the bracket, reciprocating connections associated with the bracket and actuated by the camming device, and resilient means associated with said reciprocating connections and co-operating with said camming device to drive the register.

2. In a typewriting machine, a main frame, escapement mechanism, a camming device rotating upon operation of said escapement mechanism, a standard on the main frame, a bracket secured to the standard, a register mounted upon the bracket, and a lever arm rockable upon said bracket arranged to transpose the rotary motion of said camming device into reciprocating motion and thereby operate the register.

3. In a typewriting machine, a main frame, escapement mechanism, a camming device rotating upon operation of said escapement mechanism, a standard on the rear of the frame, a bracket mounted upon the rear of the standard by means of a single screw-threaded stud and nut, whereby said bracket may be moved about said stud as a pivot, a counter mounted upon the bracket, means for

driving the counter, including a ratchet-wheel fixed to the shaft of the counter, a pawl-carried member for driving the ratchet-wheel, and a lever fulcrumed at a point between the ends thereof upon the bracket to provide a pair of arms, one of said arms being connected to said pawl-carried member, and the other of said arms arranged to be actuated by the camming device to cause the counter to be operated, and means associated with said bracket and standard for moving said bracket about its pivot to vary the position of said second-named arm with respect to the camming device.

4. In a typewriting machine, a main frame, escapement mechanism, a camming device rotating upon operation of said escapement mechanism, a standard on the rear of the frame, a bracket mounted upon the rear of the standard by means of a single screw-threaded stud and nut, whereby said bracket may be moved about said stud as a pivot, a counter mounted upon the bracket, means for driving the counter, including a ratchet-wheel fixed to the shaft of the counter, a pawl-carried member for driving the

ratchet-wheel, and a lever fulcrumed at a point between the ends thereof upon the bracket, to provide a pair of arms, one of said arms being connected to said pawl-carried member, and the other of said arms arranged to be actuated by the camming device, resilient means co-operating with said camming device for operating the counter, and means carried by said bracket and associated with the standard for moving said bracket about its pivot to vary the position of said second-named arm with respect to the camming device.

5. In a typewriting machine, a main frame, escapement mechanism, a camming device rotating upon operation of said escapement mechanism, a standard on the rear of the frame, a bracket mounted upon the rear of the standard by means of a single screw-threaded stud and nut, whereby said bracket may be moved about said stud as a pivot, a counter mounted upon the bracket, means for driving the counter, including a ratchet-wheel fixed to the shaft of the counter, a pawl-carried member for driving the ratchet-wheel, a retaining pawl for the ratchet-wheel, and a lever fulcrumed at a point between the ends thereof upon the bracket, to provide a pair of arms, one of said arms being connected to said pawl-carried member, and the other of said arms arranged to be actuated by the camming device, resilient means co-operating with said camming device for operating the counter, and means carried by said bracket and associated with the standard for moving said bracket about its pivot to vary the position of said second-named arm with respect to the camming device.

6. In a typewriting machine, a main frame, a standard on the frame, a bracket and registering mechanism pivotally mounted, as a unit, upon said standard, means for driving said registering mechanism, and means carried by said bracket for adjusting the same angularly about its pivot, so as to vary the position of said registering mechanism with respect to its driving means.

7. In a typewriting machine, a main frame, a standard on the frame, a bracket and registering mechanism, pivotally mounted, as a unit, upon said standard, means for driving said registering mechanism, and means carried by the bracket and arranged to be adjusted against said standard to cause the bracket and registering mechanism to be shifted bodily, as a unit, about its pivot, and thereby adjust the position of the registering mechanism with respect to its driving means.

8. In a typewriting machine, a main frame, a standard on the frame, a bracket and registering mechanism pivotally mounted, as a unit, upon said standard, means for driving said mechanism, and a pair of set-

screws carried by the bracket and arranged to be adjusted against the standard to cause said unit to be shifted angularly about its pivot, and thereby adjust the position of 5 the registering mechanism with respect to its driving means.

9. In a typewriting machine, a main frame, a standard on the frame having an outer face and a side face, a bracket and 10 registering mechanism, pivotally mounted, as a unit, upon said outer face, and means for driving the mechanism, said bracket including a pair of ears spaced from and overlying the side face of the standard, and set- 15 screws passing in threaded engagement through the ears and arranged to be adjusted against said side face, to cause said unit to be moved angularly about its pivot, for adjusting the position of the registering 20 mechanism with respect to its driving means.

10. In a typewriting machine, a main frame, a standard on the frame having an outer and a side face, a bracket including

a body and registering mechanism, pivotally mounted, as a unit, upon said outer face, and means for driving the mechanism, said bracket including a pair of ears disposed at right angles to the body of the bracket, to overlie the side face of the standard, and set-screws passing in threaded engagement through the ears, for adjustment against said side face, to cause the unit to be moved angularly about its pivot, for varying the 25 position of the registering mechanism with respect to its driving means. 30

11. In a typewriting machine, carriage- escapement mechanism including a revoluble cam, a bracket pivotally mounted on the frame of the machine, a register fixed to the 40 bracket, driving connections for the register, including an arm rocked by said cam whereby to operate the register, and means for adjusting said bracket about its pivot whereby to adjust the position of said arm 45 relatively to the cam. 35

ALFRED G. F. KUROWSKI.

CERTIFICATE OF CORRECTION.

Patent No. 1,674,599.

Granted June 19, 1928, to

ALFRED G. F. KUROWSKI.

It is hereby certified that the above numbered patent was erroneously issued to "Underwood Typewriter Company", of New York, N. Y., a Corporation of Delaware, whereas said patent should have been issued to "Underwood Elliott Fisher Company", of New York, N. Y., a Corporation of Delaware, as shown by the records of assignments in this office; and that the said Letters Patent should be read with this correction therein that the same may conform to the record of the case in the Patent Office.

Signed and sealed this 31st day of July, A. D. 1928.

(Seal)

**M. J. Moore,
Acting Commissioner of Patents.**
